UNITED STATES PATENT OFFICE.

LEWIS LEWISON, OF HAMILTON, ONTARIO, CANADA, ASSIGNOR TO THE CONE COMPANY OF AMERICA, OF NEW YORK, N. Y., A CORPORATION OF NEW YORK.

TRIMMING DEVICE FOR ICE-CREAM-CONE-MAKING MACHINES.

Application filed November 26, 1920. Serial No. 426,548.

To all whom it may concern:

Be it known that I, LEWIS LEWISON, a subject of the King of Great Britain, of the city of Hamilton, in the county of Wentworth, in the Province of Ontario, Canada, have invented certain new and useful Improvements in a Trimming Device for Ice-Cream-Cone-Making Machines, of which the following is the specification.

10 My invention relates to a trimming device for ice cream cone making machines patented by me in the Dominion of Canada under No. 186,239 on the 27th August, 1918, and in the United States under No. 1,289,209 15 on the 31st Dec. 1918. My present invention refers particularly to a trimming device for the edge of the cone and the object of my invention is to devise an extremely simple, and efficient means, where- 20 by the top edge of the cone may be accurately and smoothly trimmed prior to its leaving the mold.

My invention consists of a mold the top edge of which has an annular steplike double recess terminating in a bottom sharp edge and an intermediate sharp edge, and a co-acting core having a washer secured at the upper end, the edge of which is designed to fit the lower recess and is provided with peripheral recesses and an under inclined bevelled edge, which is designed intermediate of its width to rest on the bottom sharp corner edge of the lower recess, and a cap located above the washer, the core, washer and cap being secured together by a central bolt, the parts being arranged and constructed in detail as hereinafter more particularly explained.

Fig. 1, is a side elevation showing the 40 position of the mold.

Fig. 2, is a vertical section through the mold.

Fig. 3, is a sectional plan of the washer.

Fig. 4, is a cross section of the washer.

45 In the drawings like letters of reference indicate corresponding parts in each figure.

1 is the table, 2 the central shaft and 3 an arm secured to the central shaft and carrying a rib 4. 5 is the mold, which is held 50 in the ends of the separable arms 6.

The mold 5 comprises the mold proper 7 having a conical portion 7' and the horizontal portion 7", whereby it is held in the end of the arm 6. The interior of the mold 55 is formed with a double annular recess or

more properly two recesses 8 8'. The lower recess 8 has a sharp bottom edge 8" and the top recess has a sharp bottom edge 8'. The top of the mold terminates in an annular flange 9 as indicated. 10 is the core 60 at the top of which is located a washer 11 having peripheral recesses 12 and a bottom bevelled edge 13, which rests intermediate of its width when the core is forced home upon the sharp bottom corner 8". 13' is 65 an arm, which is located above the washer 11 being secured thereto by a bolt 14. The core is suitably secured to the arm 13' (see Fig. 2).

It will be noticed that there is an annular 70 space between the bottom edge of the arm 13' and the recess 8' and also that there is a space between the periphery of the arm 13' and the flange 9.

When the mold is filled with batter and 75 the core is being brought down into the position shown in Fig. 2, the surplus batter, which is very small will escape through the recess 12 and around the recesses 8 and 8' and between the periphery of the cap 13 80 and the flange 9. Very little, if any, gets over the top of the flange 9.

When the mold is in the position shown 85 in Fig. 2 and, therefore, is closed for baking the bevelled edge 13 of the washer will rest intermediate of its width upon the sharp corner 8". When the baking has partially taken place and the batter is in a semi-plastic state pressure is exerted by the rib 4 on the end of the arm 3 and this pressure 90 bringing the bevelled edge against the sharp corner 8" serves to very efficiently and evenly trim off the top edge of the cone.

It will be seen that the means, which I now employ to trim the top edge is very 95 simple and such trimming is effected prior to the discharge of the cone from the mold, which is an important desideratum.

What I claim as my invention is:

1. A trimming device for ice cream cone making machines comprising a mold formed with a lower interior recess at the upper end of the conical portion terminating in a sharp corner, and a core provided with a flaring upper end bevelled at its lower side and designed to rest intermediate of its width upon the sharp corner to form a severing means. 100

2. A trimming device for ice cream cone making machines comprising a mold formed with a lower interior recess at the upper 105

110

end of the conical portion terminating in a sharp corner, and a core fitting the mold, a washer located at the upper end of the core and provided with a bottom bevelled edge designed to rest against the sharp corner of the bottom interior recess, and means for securing the washer in place.

3. A trimming device for ice cream cone making machines comprising a mold formed with a lower interior recess at the upper end of the conical portion terminating in a sharp corner, and a core fitting the mold, a washer located at the upper end of the core and provided with a bottom bevelled edge designed to rest against the sharp corner of the bottom interior recess, means for securing the washer in place,

ing the washer in place, the washer being provided with a peripheral recess.

4. A trimming device for ice cream cone making machines comprising a mold formed with a lower interior recess at the upper end of the conical portion terminating in a sharp corner, and a core fitting the mold, a washer located at the upper end of the core and provided with a bottom bevelled edge designed to rest against the sharp corner of the bottom interior recess, a cap loosely fitting within the top of the core and means for securing the core, washer and cap together.

LEWIS LEWISON.
